GARFIELD A. WOOD, OF DETROIT, MICHIGAN.

TRUCK-BODY CONSTRUCTION.

1,292,204.

Specification of Letters Patent.

Patented Jan. 21, 1919.

Application filed January 5, 1918. Serial No. 210,416.

To all whom it may concern:

Be it known that I, GARFIELD A. Wood, a citizen of the United States, and residing at Detroit, in the county of Wayne and State 5 of Michigan, have invented a new and Improved Truck-Body Construction, of which the following is a specification.

The present invention relates to truck bodies, more particularly to the type of body which is tiltable about a transverse horizontal axis near its rear end and in which the latter is closed by a door that is swingable about a horizontal axis near its upper edge. It is, however, applicable to car bodies and 15 other tilting hoppers.

The object of the invention is to provide a strong neat appearing body from which the material is rapidly and completely discharged at the rear as the front end is lifted, 20 and to which a standard door construction is applicable regardless of considerable variation in the depth. The invention will be more fully understood from a consideration of the following description of a preferred 25 embodiment, and from the attached claims wherein the novel features are more definitely pointed out.

In the drawings, Figure 1 is a fragmentary side view of the rear end of a truck 30 showing a preferred embodiment of the invention. Fig. 2 is a rear elevation of the body. Fig. 3 is a central longitudinal vertical section corresponding to Fig. 1, the body being in elevated position and the door being 35 open. Figs. 4 and 5 are sections on the lines 4-4 and 5-5, respectively, of Fig. 1.

The side bars 1 of the body are swingable about horizontal pivots 2 that are mounted in brackets 3 in the usual way, it being understood that the brackets in turn are secured to the rear end portion of the chassis frame 3¹. Extending across the side bars at intervals are the cross bars 4 whereon the hopper 5 rests and to which it is riveted or 45 otherwise secured. In order to insure a proper discharge of bulk material, say coal or earth, therefrom, it is preferred to construct the main portion of the body of what either is, or is in effect, a single sheet of 50 metal; that is, if any seam is present it is arranged longitudinally of the body so as not to interfere with the free flow of material toward the rear.

It is desirable to merge the sides into the bottom gradually, as shown at 6, so that no sharp corners exist wherein the material

may become lodged. This general construction is well-known.

Were the sides simply extended upwardly each in a single vertical plane, the construction would be relatively weak; and in order to strengthen the hopper against bulging, as well as for the purpose of materially increasing the capacity, particularly with reference to top load, the upper portions of the 60 metal of the sides are inclined outwardly at 8, then bent inwardly to form horizontal webs 9 and finally turned downwardly, as shown at 10, to do away with the sharp edges that might otherwise cut into bags of 65 cement or the like, and to give strength 70 against bending.

The side construction just described, if continued fully to the rear end, would greatly complicate the problems incident to 75 the construction of the door and its mounting; again, the bodies are made in different capacities, the change being brought about and determined principally, if not wholly, by varying the height of the sides; it is also 80 desirable to secure a rapid and free discharge of the material therefrom in the smaller bodies, as well as in the largest sizes, which could not be obtained if the door were mounted to swing about an axis at 85 substantially the upper level of the sides. To meet these several conditions and to render the door itself standard, that is, the same for the several different sizes of bodies, each flange 9-10 is notched and trimmed 90 and thereafter bent inwardly (together with the corresponding part 12 of the inclined element 8) until the edges of the notch meet along the line 13 whereupon the trimmed end 14 of the flanges coincides with the vertical plane of the corresponding main portion of the side. Rearwardly of the part 12, the metal stands in the plane of the main portion of the side and is continued upwardly, as indicated at 15, (preferably by 100 means of a separate plate welded to the main portion of the corresponding side along the line 15', or riveted to said main portion) to a level considerably above the flanges 9. The plate 15 may be omitted. Those portions 105 of each flange 9 on opposite sides of the corresponding line 13 are finally connected by the strap or gusset plate 16. Then by riveting or welding around the extreme rear end the reinforcing bar 17, preferably of angle 110 cross-section, and by continuing it upwardly to the top of the portion or plate 15, there

is afforded a strong neat construction the upper ends of which may be joined by the cross bolt 18 upon which the door is hung by means of its straps 19. The metal of the body is slotted at 26 opposite the bar 17 to allow it to be pressed smooth against the bar, during which operation the slit assumes the form of a V as shown in Fig. 3. When the body is tilted by any suitable hoisting mechanism (not shown) and the door is set free, the latter swings out into the position indicated in Fig. 3 and provides a large opening through which the material may freely flow. By making the upstanding portion the same height in all cases, it is evident that a door suitable for one size of body is equally well adapted to another.

The construction of the door may vary; preferably, however, it comprises a sheet metal plate 20 the upper edge of which is turned inwardly at 21 over the bolt 18 and terminates in a downturned flange or rib 22. This plate may be reinforced by the flat U-shaped bar 23 conforming substantially to the edge of the body metal 5 and arranged to bear on the bar 17, and may have riveted or welded thereto a striker bar 24 with which the latch 25, (preferably that disclosed in my U. S. Patent No. 1223462, granted April 24, 1917) cooperates.

The details of construction may be varied to some extent without departing from the spirit of my invention, and I do not, therefore, wish to be limited otherwise than as indicated by the subjoined claims.

I claim:

1. In a hopper pivoted to swing about a horizontal axis near one end thereof, a trough shaped sheet metal body portion having an open end and having the upper edges of its sides inclined outwardly from points slightly forward of the open end, the body portion being extended upwardly at the open end in the form of metal sheets located, respectively, substantially in the plane of the corresponding side and considerably beyond the level of the upper edge of the corresponding inclined portion of the side, means for reinforcing the edge of the sheet metal at said open end to substantially the full height of said upwardly extending portions, and a door mounted to swing outwardly about a horizontal axis passing through the upper ends of said reinforcing means.

2. A truck body comprising a sheet metal trough having an open rear end and having its side portions flaring outwardly and finally turned inwardly to form longitudinal stiffening webs, said webs being notched near their rear ends, and the extreme rear end portions of the webs being bent inwardly at the notches at an angle to the remainder thereof, the trough extending upwardly at the rear ends beyond the level of

the flanges in the form of plates each fixed to the corresponding side portion, a horizontal cross-bolt joining the upper ends of said plates, and a door hung on the cross-bolt and arranged to close the open end of 70 the trough.

3. A tiltable truck body comprising a sheet metal bottom and sheet metal sides, the latter flaring outwardly from points slightly forward of their rear ends, said flaring portions merging into inturned stiffening webs, the metal of the sides being continued upwardly rearwardly of the flaring portions beyond the level of the webs, a reinforcing bar passing entirely around the outside of 80 the body at the rear end and stiffening said upwardly extending portions, a cross member connecting the upper ends of the reinforcing bar, and a door hung on the cross-bar and adapted to swing in respect thereto. 85

4. A tiltable hopper having sheet metal sides the upper portions of which are inclined outwardly throughout the greater part of their length and provided with inwardly bent substantially horizontal stiffening webs, the extreme rear ends of the sides extending upwardly considerably beyond the level of the corresponding web, the front edges of the upwardly extending portions being inclined downwardly and forwardly 95 and merging into the corresponding outwardly inclined side portions through the medium of substantially triangular portions inclined to both longitudinal vertical and transverse vertical planes of the hopper, a connecting member extending across between the upper ends of the upwardly extending portions, and a swingable door supported on said connecting member and arranged to close the end of the hopper. 100

5. A truck body having a side formed of sheet metal, said side having a main portion arranged substantially in a vertical plane, an upper portion inclined outwardly therefrom at a considerable angle, a web extending inwardly from the extreme upper edge of said inclined portion and arranged substantially in a horizontal plane and serving to reinforce said inclined portion against bulging, and a rib extending downwardly 115 from the web at the inner edge thereof to reinforce the latter against sagging, said rib being positioned in a plane outside of the plane of said main portion of the side.

6. A truck body having a side formed of 120 a single sheet of metal including a main portion arranged substantially in a vertical plane, an upper portion inclined outwardly therefrom, a web arranged substantially in a horizontal plane and reinforcing said inclined portion against bulging, and a rib extending down from the web at the inner edge thereof and reinforcing the latter against sagging. 125

7. In a vehicle body, a side construction 130

including a sheet of metal having a main portion arranged substantially in a vertical plane, an upper portion inclined outwardly therefrom, a web arranged substantially in a horizontal plane and reinforcing said inclined portion against bulging, and another portion bent from the web along its inner edge to reinforce the web against vertical loads, the web being notched transversely and bent inwardly together with a continuation of the inclined portion near the rear end to merge substantially into the above mentioned vertical plane.

8. A vehicle body comprising side constructions having upper portions flaring outwardly and upwardly away from one another for the greater portion of their length, said upper portions being bent gradually back substantially into the plane of the rest 20 of the corresponding side construction near the rear end thereof, a reinforcing bar conforming to the outside of the extreme rear end of the body and extending upwardly at each side considerably beyond the upper 25 edge of the corresponding side construction, and a door supported on the upper ends of said bar to swing about a horizontal axis to close the rear end of the body.

9. A vehicle body comprising side constructions having upper portions flaring outwardly and upwardly away from one another for the greater portion of their length, said upper portions being bent gradually back substantially into the plane of the rest 30 35 of the corresponding side construction near the rear end thereof, a single reinforcing bar embracing both sides of the body at the extreme rear end thereof, and a door supported by said bar to swing about a horizontal axis considerably above the upper edge of

the corresponding side construction to close the rear end of the body.

10. In a vehicle body, a side construction including a sheet of metal having a main portion arranged substantially in a vertical plane, an upper portion inclined outwardly therefrom, a web arranged substantially in a horizontal plane and reinforcing said inclined portion against bulging, the web being notched transversely and bent inwardly 45 50 together with a continuation of the inclined portion near the rear end to merge substantially into the above mentioned vertical plane.

11. In a vehicle body, a side construction including a sheet of metal having a main portion arranged substantially in a vertical plane, an upper portion inclined outwardly therefrom, the metal extending inwardly considerably from the upper edge of said 55 60 upper portion to form a reinforce for the latter, said reinforce being notched transversely and bent inwardly together with a continuation of the inclined portion near the rear end to merge substantially into the 65 above mentioned vertical plane.

12. A tiltable truck body comprising a sheet metal bottom and sheet metal sides, the latter flaring outwardly from points slightly forward of their rear ends, said flaring portions merging into inturned stiffening webs, the metal of the sides being continued upwardly rearwardly of the flaring portions beyond the level of the webs, a reinforcing bar passing entirely around the outside of 70 75 the body at the rear end and stiffening said upwardly extending portions, and a cross member connecting the upper ends of the reinforcing bar.

GARFIELD A. WOOD.
